UNITED STATES PATENT OFFICE.

FREDERICK W. SCHMIDT, OF PHILADELPHIA, PENNSYLVANIA.

PROJECTING LANTERN.

Application filed April 18, 1924. Serial No. 707,352.

My present invention comprehends a novel construction and arrangement of a projecting lantern which is especially adapted to be employed to project in a desired direction the representation of a picture, drawing, statue, or other solid object so that it can be reproduced.

It further comprehends a novel lantern wherein the objectional heat of the lamp is overcome by forming the casing of a front wall and two hinged sides.

It further comprehends novel lamp supports, novel means for adjusting reflectors, novel means for mounting a mirror, a novel construction of an adjustable support for the picture or article to be projected, and novel means for supporting a cover.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is however to be understood that this embodiment is typical only and that the various instrumentalities of which my invention consist can be variously arranged and organized, and that the invention is not limited to the precise arrangement and organization of these instrumentalities as herein set forth.

Figure 1 is a top plan view of a projecting lantern, embodying my invention.

Figure 2 is a section on line 2—2 of Figure 1.

Figure 3 is a front elevation.

Figure 4 is a rear elevation.

Figure 5 is a section on line 5—5 of Figure 4.

Figure 6 is a section on line 6—6 of Figure 4.

Similar numerals of reference indicate corresponding parts.

Referring to the drawings:

1 designates a projecting lantern, embodying my invention. Instead of employing a closed casing or cabinet which becomes highly heated due to the light from the lamps, the casing consists of a front wall 2 to which are secured by means of the hinges 3, the side walls 4. The front wall 2 is provided with the guides 5, in which are vertically adjustable the angle bars 6. 7 designates a lens holder slide which engages

guides on the wall 2. The front 2 is provided with the brackets 8 which support the lamp supports 9 within which the rods 10 telescope, said rods being secured in their adjusted position by means of the fastening devices 11. The rods 10 carry the lamp sockets 12 within which are the lamps 13. The rear face of the front 2 carries the guides 14 in which are vertically and rotatably adjustable the angle rods 15 which are fixed in position by means of the fastening devices 16. 17 designates reflectors for the lamps, which are adjustably mounted on the lateral extending portions of the rods 15 and which are secured in their adjusted position by means of the fastening devices 18. The front face of the front 2 is provided with sets of mirror supporting devices 19, 20, 21 and 22, respectively, which are arranged at the top and bottom portions and at the side portions of the lens holder 7. 23 designates a mirror which is movably carried by a desired support 19, 20, 21 or 22 by means of the rod 24. The chain 25 fixed to the front 2 is adapted to engage one of the pins 27 on the frame of the mirror 23 in order to secure said mirror in the position to which it is adjusted. A standard 28 has adjustably mounted thereon the brackets 29 which are secured in their adjusted position by means of the fastening devices 30. These brackets 29 carry the grooved members 31 and 32, respectively, which are adapted to receive and clamp the picture, photograph or other object 33 which it is desired to reproduce.

The rods 6 are adapted to support the cover 34 and these rods are vertically adjustable and can be fixed in their adjusted position by means of the set screws 35, see Figure 3. 36 designates a lens which is longitudinally slidable in the lens holder 7 so that its carrier can be adjusted to any desired position, and different size lenses can be employed as may be desired.

The operation will now be apparent to those skilled in this art, and is as follows:

The object which is to be projected such as a photograph or picture, is secured on the object holder 27, as will be understood by reference to Figure 2. A solid object such as a statue, or an inanimate or animate object is placed in the same relative position with respect to the lens as is the object 33.

The lamps 13 are illuminated, and the reflectors 17 are adjusted so that the light

rays will pass to the object and therefrom to the lens 36 and to the mirror 23 which latter reflects the light rays on to any desired surface, so that they will be visible to the operator, and so that, if desired, the representation projected can be outlined, colored or otherwise treated.

The cover 34 is adjustable in height so as to keep the light within the cabinet, and, since the rear of the casing or cabinet is more or less open, the heat from the lamps is permitted to escape so that there can be no overheating or discoloring of the pictures or other object which are to be projected. The position of the mirror 23 can be changed so that the light can be thrown from one side to the other or in an upward or a downward direction. The position of the object holder can be varied as may be desired in order that the desired portion of the object or the entire object can be projected.

The lamps 13 are capable of vertical adjustment, and the reflectors 17 can be adjusted relatively to the lamps 13, so that the proper projection of the light rays will be obtained.

The slides 7 are removable so that they can be replaced by other slides, the tubes of which are of different diameters to receive lenses of different diameters. If desired the front and side walls may have legs 37 fixed in their adjusted position by fastening devices 38.

It will now be apparent that I have devised a new and useful projecting lantern which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention, what

I claim as new and desire to secure by Letters Patent, is:

1. In a projecting lantern, a casing consisting of a front wall having a light opening and side walls hinged to the front walls, a lens for said light opening, lamp supports carried by said front wall, reflectors for said lamps adjustably connected with the casing, a mirror to deflect rays of light from said lens, and means common to said mirror and said front wall to movably connect them above or below or at either side of said lens so that the mirror can be angularly adjusted either up and down or from side to side. 55

2. In a projecting lantern, a casing consisting of a front wall having a light opening and side walls hinged to the front walls the rear of said casing being open, a lens for said light opening, lamp supports carried by said front wall, reflectors for said lamps adjustably connected with the casing, a mirror to deflect rays of light from said lens and means common to said mirror and said front wall to movably connect them above or below or at either side of said lens so that the mirror can be angularly adjusted either up and down or from side to side, and means carried by said front wall to retain said mirror in the position to which it has been adjusted. 70

3. In a projecting lantern, a casing consisting of a front wall having a light opening and side walls hinged to said front walls, a lens carrier vertically slidable on said front wall in proximity to said opening, a lens for said lens carrier, lamp supports on the rear face of said front wall, standards adjustably connected with said walls, mirror supporting means above, below, and at each side of said lens carrier, a mirror to deflect rays of light from said lens and adapted to be detachably connected with said mirror supporting means at either side or above or below said light opening, and means to retain said mirror in the position to which it is adjusted. 80

FREDERICK W. SCHMIDT.
